UNITED STATES PATENT OFFICE.

FREDERICK M. WHYTE, OF TARRYTOWN, NEW YORK, ASSIGNOR TO HUTCHINS CAR ROOFING COMPANY, OF DETROIT, MICHIGAN, A CORPORATION OF MICHIGAN.

FIRE-DOOR.

1,177,668.

Specification of Letters Patent.

Patented Apr. 4, 1916.

Application filed June 1, 1914. Serial No. 842,210.

To all whom it may concern:

Be it known that I, FREDERICK M. WHYTE, a citizen of the United States of America, residing at Tarrytown, in the county of 5 Westchester and State of New York, have invented certain new and useful Improvements in Fire-Doors, of which the following is a specification, reference being had therein to the accompanying drawings.

10 The invention relates to fire doors for furnaces, of that type in which the door opens inwardly and in closed position rests against an annular seat on the door frame. Doors of this type are particularly adapted

15 for use in connection with a pneumatic or motor-operated opening and closing mechanism, and have the advantage that in open position the door is inside of the door frame and does not obstruct free access to

20 the opening. On the other hand, a defect of construction as heretofore made is that the door can only be detached by the complete disengagement of the door frame from the boiler or furnace wall.

25 It is one of the objects of the present invention to obtain a construction in which the door may be easily removed without detachment of the door frame, and a further object is to obtain a simple and practical

30 construction to manufacture.

In the drawings: Figure 1 is a front elevation of the door frame and door; Fig. 2 is a vertical central section through the same shown in relation to the furnace wall 35 and door opening; and Fig. 3 is a plan view of one side of the frame.

A is the furnace wall, which, as shown, is of the usual hollow construction forming a water jacket, the inner and outer sheets being flanged at B and B' to overlap each 40 other and form the door opening.

C is the door frame which has an annular flange C' secured by bolts or studs D to the furnace wall.

45 To form a seat for the door, and also to provide for the inward opening of the latter, the frame C is formed with an outwardly-projecting portion C² terminating in an outwardly and upwardly inclined wall apertured to form the door opening D'. Surrounding this opening and on the inner face of the inclined wall is an annular seat E forming a closed-door seat for the door.

F is the door which is hinged at its upper 55 end and adapted when swung inward to lie

adjacent to the top of the door opening, as shown at V. The door is hinged by attaching the same to a rock shaft G through the medium of straps H, and the rock shaft is journaled in suitable bearings in the frame 60 and provided with an operating mechanism, attached preferably between the bearings. As shown, this operating mechanism is formed by an actuating rock-arm I of the rock shaft G, which is connected by a pitman 65 J with a piston in a cylinder K arranged vertically and mounted upon a bracket L projecting outward from one side of the door frame.

The door F to properly seat upon the 70 frame is of greater dimensions than the door opening D'. This would prevent its insertion through the door opening, and if the frame were of integral construction it 75 would be necessary to detach said frame from the furnace wall to remove the door. Inasmuch as it is frequently necessary to remove the door for repairs, such for instance as the renewal of the lining plate W therefor, and also as the door frame is a 80 large and heavy casting, the necessity for detaching the latter is objectionable. With my improved construction, I have avoided this objection by forming the door frame with a detachable cap section M. This 85

covers an opening in the top of the frame of sufficient area for the insertion and removal of the door, and the cap in connection with the frame may form a split bearing or journal for the door trunnions or rock shaft G. 90 Thus, as shown, the cap M is provided with side flanges N which are bolted to complementary side flanges O on the frame C, and when the shaft G passes through them, the flanges are curved around the shaft at 95 P and may be used for the shaft bearings. Supporting bearings for the shaft are also provided at Q and R, Q being a bifurcated bearing member at the upper and outer end of the flange L, and R being another form; and either of these can be used at both places. The rock arm I is arranged preferably between the bearings Q and P on one side of the frame, and a hand operated lever 100 may be attached at S, preferably between the corresponding bearings on the opposite sides of the frame.

With the construction as described, in use, whenever it is necessary to remove the door the cap M is detached, which permits 110

of readily disengaging the shaft G from the bearings Q and R and lifting the door through the opening disclosed by the removal of the cap.

5. What I claim as my invention is:—

1. The combination with a furnace, of a door frame therefor having an annular flange secured to the furnace wall, an outwardly-projecting portion having an inclined wall apertured to form the door opening, and flanges projecting outward from the opposite sides of said annular flange, a door seated within said frame on the annular bearing surrounding said door opening, a detachable cap for covering an opening in the top of said outwardly-projecting portion, through which the door may be inserted or withdrawn, a rock-shaft

10 on which the door is hung, and bearings for said shaft formed on said flanges, projecting outward from the annular flange of said frame.

15 2. The combination with a furnace, of a door frame therefor, having an annular flange secured to the furnace wall, an open-topped outwardly-projecting portion having an inclined wall formed with a door opening and with an annular door seat inclosing said opening and having a flange projecting outwardly from said annular flange at each side of said outwardly-projecting portion, formed with a bearing, a door mounted within said outwardly-projecting portion of the frame normally resting upon said annular seat, a detachable cap for covering the top of said outwardly-projecting portion, forming with

said portion a bearing at each side of the door opening, and a rock-shaft on which the door is hung, journaled in the last named bearings and in the bearings formed in 40 said outwardly-projecting flanges.

3. The combination with a furnace, of a door frame therefor, having an outwardly-projecting open-topped portion formed with a door opening and having an integral strip 45 separating the top opening from the door opening, a door seated upon the inner face of said frame and a detachable cap for covering the top opening of said frame, said strip having its inner and top faces normally respectively engaged by bearing portions of said door and cap.

4. The combination with a furnace, of a door frame therefor having an outwardly-projecting open-topped portion formed with 55 a door opening and having an integral strip separating the top opening from the door opening, a door seated upon the inner face of said frame, pivotal members for the door engaging the frame at each side of the door opening, a cap closing the top opening having portions engaging said pivotal members, and a common means for securing said cap to the frame and maintaining the cap engaged with said pivotal members.

In testimony whereof I affix my signature in presence of two witnesses.

FREDERICK M. WHYTE.
